UNITED STATES PATENT OFFICE.

ROBERT W. JAGENBURG, OF NEW YORK, N. Y., ASSIGNOR TO ASBESTOS SLATE ROOFING
MANUFACTURING COMPANY, INCORPORATED.

MACHINE FOR MAKING ARTIFICIAL-STONE SHINGLES, &c.

1,281,577.

Specification of Letters Patent. Patented Oct. 15, 1918.

Application filed October 12, 1915. Serial No. 55,499.

To all whom it may concern:

Be it known that I, ROBERT W. JAGENBURG, a citizen of the German Empire, and a resident of New York, in the county and State of New York, have invented certain new and useful Improvements in Machines for Making Artificial-Stone Shingles, &c., of which the following is a specification.

This invention has reference to improvements in machine for making artificial stone shingles, plates, slabs and the like from a composition of asbestos or other fire-proof materials which are thoroughly and uniformly mixed with hydraulic cement and anhydrous silicon dioxid and some water.

It is the special purpose of the present invention to produce a machine for making artificial stone shingles in one continuous operation. The mixed mass, in a plastic condition is allowed to flow from the mixer by gravity down into measuring devices which are automatically opened and closed by the rotation of the machine. From the measuring devices the measured quantities pass down into the shingle forming device wherein air pressure is applied to squeeze out the water and form the shingles, slabs or plates. An endless belt device is provided which is automatically and intermittently raised and lowered by cam arrangements so as to receive the pressed or formed shingles and transport them out of the machine.

Means are provided within the machine to produce plates of uniform thickness or shingles having a slanting surface while being rectangular at the opposite side. These shingles with slanting surface produce what architects term a beautiful shadow effect. Such tapered artificial roofing material is easier laid and nailed and more desirable than artificial shingles of uniform thickness.

In addition to these main objects means are provided on the measuring devices to allow of the escape of air while the plastic mass is filling the same. There are further devices for equalizing the compressed air pressure on the surface of each measured quantity of plastic mass within the shingle molding device. The invention further consists in the construction and arrangement of the various parts and care has been taken to produce a compact and reliable machine

which produces shingles in a relatively short period of time, all as will be fully described hereinafter with reference to the accompanying drawings in which:

Figure 1 represents in elevation, partly in section a machine for making artificial stone shingles, plates and slabs embodying in desirable form the present improvements.

Fig. 2 illustrates in longitudinal section a measuring device.

Fig. 3 shows the machine in top plan view.

Fig. 4 is a partial section of the shingle molding device with the endless belt arrangement.

Similar characters of reference denote like parts in all the figures.

In Fig. 1 of the drawing *a* represents a box containing a mixing device of any approved construction. From the bottom of the box *a*, a plurality of pipes, *3* being shown in Fig. 1, *b*, *c*, *d*, extend downwardly and connect with the measuring devices *e*, *f*, *g*. One of the measuring devices is shown in longitudinal section in Fig. 2. Each measuring device comprises an inlet valve *h* and an outlet valve *i*. Three such inlet valves *h*, *h*¹, *h*² and three discharge valves *i*, *i*¹, *i*² are shown in Fig. 1 in connection with the three measuring devices illustrated. From the casing *k* of the valve *h* a channel *j* extends upwardly. The channel permits of the escape of the air from the measuring tube *k* while the same is filling up and allows air to enter when the said tube is discharging. All the described valves are automatically opened and closed by means of special devices. Each device comprises a short lever arm *l*, *l*¹, *l*², one each connected with an inlet valve. A lever *m*, *m*¹, *m*², is pivotally connected with the free end of a short arm *l*, *l*¹, *l*². Each lever *m*, *m*¹, *m*², is pivotally connected to a short arm *n*, *n*¹, *n*², the other end of which is secured to a lower or discharge valve. Short lever arms *o*, *o*¹, *o*², are movably connected one each with the short arms *n*, *n*¹, *n*², the free ends of the arms *o* are pivotally mounted upon a bar *p*. The bar *p* performs a to and fro motion by means of an eccentric *q* mounted upon the main or driving shaft *r*. The eccentric connects with the bar *p* by means of the lever *q*¹ the top end of which is pivotally connected with a short lever arm *q*² which in turn con-

nects with the short arm α^1 secured upon the bar p . By the rotation of the eccentric a to and fro motion is imparted to the said bar p whereby the valves of the measuring devices 5 are periodically opened and closed.

The end of the bar p connects with a link s the second end of which is connected to an air inlet valve t located in an air pipe u through which compressed air is introduced 10 into the machine. Thus the inlet and discharge valves of the measuring devices are automatically opened and closed by the eccentric g during the rotation of the main shaft r and the compressed air valve t also is operated thereby and these mechanisms are so timed that the air pressure valve opens when the plastic mass has left the measuring devices that is after the discharge valves 15 had been opened.

20 The extension of each measuring tube beyond the discharge valve reaches into the pressure box v . In the upper section of the pressure box an air deflecting plate w is provided for the purpose of checking the in-rushing air from the air pressure tube and distributing it uniformly. The air thus passes under even pressure into the air chamber x . The extensions of the measuring tubes within the pressure box communicate with the space below which is adapted 25 to receive the measured quantities of the plastic mass, the molding frame v^1 of the pressure box being divided into a plurality of sections by means of bars y creating 30 thereby molding sections for the plastic mass. In order to make the molding frame v^1 of the pressure box v removable it is screwed thereto by means of screws z .

For the purpose of closing the bottom of 40 the molding frame so as to retain the plastic mass therein and mold the shingles or plates therefrom an endless belt device is provided adapted to be intermittently raised and lowered by the rotation of the main shaft. The endless belt 1 is composed of fabric adapted 45 to permit the water of the plastic mass to pass through when the compressed air pressure is applied to said mass. The belt runs over rollers 2, 3, 4, and 5.

50 Underneath the belt a stationary screen 6 is provided which rests on a grate 7. These devices are mounted in a box 8 which has a central extension 9. This extension connects with an eccentric 10 mounted upon 55 the main shaft. During the rotation of the main shaft the eccentric moves from the position indicated in Fig. 1, into the position indicated in Fig. 4 whereby the box with grate, screen and belt are raised and pressed 60 against the bottom of the pressure box. The box 8 when moved up and down is guided in the upper portion of the frame 13. The grate, screen and the section of the belt thereon are pressed against the molding frame of 65 the pressure box under an inclined plane whereby tapered shingles result. As shown in Fig. 1, the grate with screen thereon is secured to a hinge 11 on one side and a set screw 12 is provided on the other side whereby the machine may be adjusted. In this 70 way plates of uniform thickness may be produced with this machine as well as tapered shingles. The device shown in Fig. 4, however is stationary for the production of one style of plates or shingles. In this modified 75 form a perforated disk w^1 is shown in place of the air deflector w to equalize the air pressure.

The endless belt is tensioned by means of springs 14 of which one is shown in Fig. 1. 80 In order to transmit the motion of the main shaft to the belt a gear wheel 15 is mounted on the main shaft engaging a gear wheel 16 on a separate shaft 17. Upon this shaft there is mounted a Geneva wheel 18 with 85 a stop pin 19 to produce the intermittent movements described. The gear wheel 16 actuates a bevel gear 20 on a shaft 21 which in turn actuates a bevel gear 22 upon a shaft 23. This shaft is mounted in bearings upon the frame 24. The shaft 23 supports the roller 3 over which the belt passes.

Assuming that the main shaft rotates then 90 the eccentric g opens the inlet valves of the measuring devices and closes the discharge valves of the same. Now the measuring tube is filled and upon further rotation of the eccentric g the inlet valves are closed 95 and the discharge valves opened permitting the contents to flow down into the space 100 underneath the air deflector w of the pressure box v . Properly timed therewith by the gear wheels and Geneva wheel with stop pin and the bevel gears the eccentric 10 raises the box 8 with the grate 7, the screen 105 6 and the belt 1 and forces them against the bottom of the molding frame of the pressure box to retain the contents of the measuring tubes in the sections of the said frame. Now the air pressure valve t is automatically 110 opened and the compressed air passes through the tube u onto the air deflector w into the air chamber x . The compressed air thus is uniformly distributed. If a perforated disk w^1 is employed the air passes 115 through its perforations into the air chamber x^1 . The air presses the water out of the plastic mass through the fabric of which the endless belt is composed thereby forming 120 the shingles or plates in the molding sections of the molding frame. When the air valve is open the discharge valves of the measuring devices are closed and the inlet valves open. By the continued rotation of the main shaft the eccentric 10 descends with 125 the screen and grate and the section of the belt just on the screen. The springs 14 compensate the up and downward movement of the belt. The moving belt transports the molded shingles to the table 25 from where 130

they are taken to be finished in suitable machines by very high pressure such as hydraulic pressure.

With the described construction of a shingle, plate or slab molding machine a continuous operation is effected with very little help.

I claim as my invention:

1. A machine for a continuous production of artificial tapered shingles or the like, comprising measuring devices, a pressure box into which said measuring devices lead and which has an open bottom, a molding frame arranged at a slant in said open bottom, an endless belt fed longitudinally of and below said molding frame, a screen over which said conveyer is stretched, a vertically movable member in which said screen is supported, compressed air supplying means leading into said pressure box, means for periodically and intermittently operating the said measuring devices, compressed air supplying means and the conveyer, and means for periodically and intermittently raising said member and pressing said screen and conveyer against the said molding frame.

2. A machine for continuously making tapered artificial shingles, plates, etc., comprising measuring means, a pressure box having an open slanting bottom and into which said measuring means lead, compressed air supplying means leading into said pressure box, a molding frame arranged in said open bottom of said pressure box, an endless belt fed longitudinally of and below said molding frame, a screen over which said belt is stretched, a vertically movable member in which said screen is supported, means for periodically and intermittently operating said measuring devices, compressed air supplying means and said belt, and means for intermittently raising said member and pressing said screen and belt against the said molding frame.

3. A machine for continuously making 45 tapered artificial stone shingles, plates, etc., comprising measuring devices, a pressure box in which said measuring devices terminate and which has an open and slanting bottom, a device for supplying said pressure 50 box with compressed air, a molding frame removably secured in said open bottom, an endless belt fed longitudinally of and below said molding frame, a vertically movable member, a screen pivoted at one end to and 55 adjustably supported at its opposite end on said member so as to enable to vary of angle of inclination of said screen relative to the horizontal and to thereby vary the taper of the shingles, and means for periodically and 60 intermittently imparting motion to the said parts.

4. In a machine for continuously making artificial tapered stone shingles, etc., in combination with a vertically movable screen, a 65 pressure box having an open slanting bottom and a frame removably mounted in said open bottom, said screen coöperating with the frame of said pressure box.

5. In a machine for continuously making 70 tapered artificial stone shingles, plates, etc., the combination of a pressure box having an open slanting bottom, a molding frame removably mounted in said open bottom, a spring tensioned conveyer belt pervious to 75 liquids, a vertically movable box, a screen adjustably supported in said box and over which said belt is stretched, and means for periodically and intermittently raising said box and pressing said screen and belt against 80 the said molding frame.

Signed at New York, N. Y., this 11th day of October, 1915.

ROBERT W. JAGENBURG.
